UNITED STATES PATENT OFFICE.

MAUD STRYKER, OF HOUSTON, TEXAS.

DESIGN FOR A RADIATOR CAP.

Application filed October 21, 1922. Serial No. 4,044. Term of patent 14 years.

To all whom it may concern:

Be it known that I, MAUD STRYKER, a citizen of the United States, residing at Houston, in the county of Harris and State of Texas, have invented a new, original, and ornamental Design for a Radiator Cap, of which the following is a specification, reference being had to the accompanying drawing, forming part thereof.

The figure is a front view of a radiator cap showing my new design.

I claim the ornamental design for a radiator cap as shown.

MAUD STRYKER.
